UNITED STATES PATENT OFFICE.

CHARLES LUDVIK, OF BROOKLYN, NEW YORK.

ROTARY ENGINE.

SPECIFICATION forming part of Letters Patent No. 393,567, dated November 27, 1888.

Application filed February 2, 1888. Serial No. 262,722. (No model.)

To all whom it may concern:

Be it known that I, CHARLES LUDVIK, of Brooklyn, in the county of Kings and State of New York, have invented a new and useful 5 Improvement in Rotary Engines, of which the following is a full, clear, and exact description.

This invention relates to an improvement in rotary engines in which a winged piston 10 revolves in a cylindrical steam or fluid chamber having abutment-chambers opening into opposite sides thereof, in which rotary fluid-abutments are arranged to alternately cut off the annular space around the piston and to be 15 retracted to permit the piston-wing to pass.

The object of my improvement is to provide simple and efficient means for reversing the engine and to lighten the construction, and thus reduce the friction of the working parts 20 without affecting their strength and durability.

The invention consists of certain novel combinations of parts and details of construction hereinafter fully described, and distinctly pointed out in the claims.

Reference is to be had to the accompanying drawings, forming a part of this specification, in which similar letters of reference indicate corresponding parts in all the figures.

Figure 1 is a longitudinal sectional elevation 30 of a rotary engine embodying my improvement on the line $x-x$, Fig. 2. Fig. 2 is a sectional plan view of the same on the line $y-y$, Fig. 1. Fig. 3 is an end elevation of the same. Fig. 4 is a cross-sectional elevation on the line $z-z$, Fig. 1. Fig. 5 is a perspective view of one of the rotary abutments and its driving-gear detached. Fig. 6 is a perspective view of the piston.

The engine-casing A is constructed with a 40 cylindrical piston-chamber, B, having heads C and approximately semi-cylindrical abutment-chambers D opening into opposite sides of the piston-chamber.

Within the piston-chamber B a piston, E, is 45 mounted to revolve centrally on and with a piston-shaft, G, journaled in the chamber-heads C.

The body of the piston E is made hollow of 50 opposite heads, H, and a cylindrical shell, I, rigidly connecting them, and said shell is formed with a segmental opening, J, through

and at the ends of which diverging pressure-heads K project to or nearly to the cylindrical wall of the piston-chamber and are connected at their extremities by a cylindrical segment, 55 L, forming the piston-wing F.

Each pressure-head K is made in two sections, of which the outer section laps over and is secured adjustably to the inner section by a screw-and-slot connection, K', so that the 60 outer bearing-segment, L, can be properly adjusted with reference to the cylindrical wall of the piston-chamber to completely divide the annular space around the piston-body while rotating freely in the said space. 65

A spring packing-plate, L', conforming nearly to the bearing-segment L of the piston-wing, is secured transversely at its middle thereto by a tight joint, L'', and its opposite free ends, which are pressed yieldingly against 70 the chamber-wall, have inturned flanges L''' projecting past the ends of the bearing-segment L to prevent the ends from catching on any obstruction and to better hold the plate in place. 75

In the abutment-chambers D are mounted to revolve hollow abutments M, each formed of an approximately semi-cylindrical shell, M', corresponding heads, M'', and a rigid U-shaped brace, M'', having its closed end secured 80 to the interior of the shell M' and its arms to the inside of the opposite heads M'', so as to be both light and of ample strength.

The abutments M are fixed centrally on shafts N, journaled, preferably, in adjustable 85 bearings N', held on the engine-casing and revolved from the piston-shaft G, which may be used as the driving-shaft, by outside gear-wheels, O.

The abutment-revolving gear is so arranged 90 that the semi-cylindrical abutments will alternately rotate in contact with the cylindrical piston-body, so as to cut off the annular space around the same and be retracted within the abutment-chambers during the passage of the 95 piston-wing thereby.

The opposite heads H of the piston-body are formed on their outer faces with concentric grooves P P', and the corresponding chamber-heads with fluid-openings Q Q', registering continually therewith. The piston-heads H are also formed with radial grooves 100

R R', leading outward from the respective circular grooves P P' and opening on opposite sides of the piston-wing.

The openings Q Q' in the chamber-heads 5 serve alternately either as admission or exhaust openings, and with them are connected, respectively, pipes S S', provided with three-way cocks T T' and branch pipes U U', connected to the extra ways thereof.

10 The main pipes S S' may be both connected with a steam or other fluid power supply, and the branch pipes U U' with an exhaust pipe or condenser. Then when it is desired to run the engine in the direction indicated by the 15 arrow *a* in Fig. 1 the cock T is turned to connect the pipe S with the power-supply and to close the branch exhaust-pipe U, while the cock T' is turned to cut off the pipe S' and connect the same with the branch exhaust-pipe 20 U'. The live steam or fluid will then pass through the pipe S and head-opening Q into the piston-head grooves P and R, and thence into the annular chamber-space at the left of the piston-wing, and, reacting upon the left- 25 hand abutment M, will drive the piston-wing and piston to the right, while the exhaust steam at the right of the piston-wing will pass outward through the piston-grooves P' and R', head-openings Q', pipe S', and branch exhaust- 30 pipe U'. To reverse the engine, the cocks T T' are both reversed, when the live fluid will pass to the right of the piston-wing through the pipe S' and passages previously used for the exhaust and the dead fluid out through 35 the pipe S and passages previously used for the admission, thereby causing the piston to revolve in the opposite direction.

Having thus described my invention, what I claim as new, and desire to secure by Letters Patent, is—

1. A piston for a rotary engine having a wing formed of two radially-projecting inner head-sections, outer head-sections lapping over and adjustable radially on the inner head-sections, and a cylindrical bearing-segment carried by the outer head-sections, substantially as described. 40

2. A piston for a rotary engine having a wing, the outer bearing-face of which is cylindrical, and a spring packing-plate, conforming 45 approximately to said bearing-face, secured medially thereto and provided with inturned end flanges projecting over the ends of the bearing-face, substantially as described. 50

3. A rotary piston constructed of two heads 55 rigidly connected by a cylindrical shell having a lateral opening, pressure-heads diverging radially from the center of the heads through the shell-opening, and a cylindrical bearing-segment rigidly connecting the extremities of said heads, substantially as described. 60

4. A rotary abutment for a rotary engine constructed of an approximately semi-cylindrical shell having corresponding heads, and 65 a U-shaped brace having its closed end attached to the interior of the shell and its arms attached to the inside of the heads, substantially as described.

CHARLES LUDVIK.
